DESIGN FOR A LAMP

Max Aronek, Altadena, Calif.

Application May 26, 1947, Serial No. 139,276

Term of patent 7 years

(Cl. D48—20)

To all whom it may concern:

Be it known, that I, Max Aronek, a citizen of the United States of America, residing at Altadena, in the county of Los Angeles, State of California, have invented a new, original, and ornamental Design for a Lamp, of which the following is a specification, reference being had to the accompanying drawings, forming part thereof:

In the drawings:

Fig. 1 is a front elevational view of the lamp, showing by new design;

Fig. 2 is an elevational view of the lamp looking from line 2—2 of Fig. 3;

Fig. 3 is a top view of the lamp;

Fig. 4 is a cross-sectional view of a detail taken at line 4—4 of Fig. 2; and

Fig. 5 is a cross-sectional view of the lamp taken at line 5—5 of Fig. 1.

I claim:

The ornamental design for a lamp, as shown.

MAX ARONEK.
